UNITED STATES PATENT OFFICE.

IDA CAREY, OF TUSCARORA, NEVADA.

RAIL TIE AND FASTENING.

1,132,437.

Specification of Letters Patent. Patented Mar. 16, 1915.

Application filed August 20, 1914. Serial No. 857,731.

To all whom it may concern:

Be it known that I, Ida CAREY, a citizen of the United States, residing at Tuscarora, in the county of Elko and State of Nevada, have invented certain new and useful Improvements in Rail Ties and Fastenings; and I do hereby declare the following to be a full, clear, and exact description of the invention, such as will enable others skilled in the art to which it appertains to make and use the same.

My invention relates to new and useful improvements in rail ties and fastening means therefor and resides in the provision of a concrete tie that is reinforced by a number of metallic plates and strips and is strong and durable.

An object of importance is to provide novel means coöperating with the tie to securely hold the rails in the proper position, said means being of simple construction, reliable and efficient in operation and capable of being readily attached and detached relative to the tie, said fastening means also serving to increase the rigidity of the tie and prevent wear thereon due to constant pressure of the rails on the tie.

Another object is to provide a rail tie and fastener of the character described that is of an extremely simple construction, is reliable and efficient in operation, capable of being readily assembled and disassembled and which is inexpensive to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a plan view showing a track constructed with my improved ties, Fig. 2 is a fragmentary longitudinal sectional view, taken vertically through one of the ends of the tie showing the fastening means in operative position and a rail thereon, Fig. 3 is a transverse sectional view taken through one of the ends of the tie showing the rail thereon in side elevation, Fig. 4 is a detail perspective view of one of the ends of the tie showing the clamping means for the rails removed, Fig. 5 is a detail perspective view of one of

the bracing members for the ends of the tie, Fig. 6 is a detail perspective view of a portion of the rail supporting plate showing the construction of the ends thereof to co-operate with the bracing members for the ends of the tie illustrated in Fig. 5, Fig. 7 is a detail view of one of the locking screws, Fig. 8 is a detail perspective view of a cam hook to co-operate with the locking screw.

Referring to the drawings by characters of reference the numeral 1 designates as an entirety the concrete body portion of my improved tie, which body portion is of the ordinary length and width as compared to the wooden ties preferably and is provided upon its upper and lower faces with longitudinal channels 2 and 3 in which are mounted rectangular and metallic plates 4 and 5. These channels and plates extend the length of the tie and the plates are flush with the ends thereof. The outer faces of the plates are flush with the upper and lower faces of the body portion 1.

Formed adjacent to the ends of the tie in the side faces thereof are opposed vertical channels or recesses 6 designed to receive the side plate portions 7 of an approximately U-shaped bracing member 8 so that the outer faces of the plate 7 are flush with the outer side faces of the tie. An opening 9 is formed in the body portion of the U-shaped member 8 intermediate the ends thereof and alines with openings in the plates 4 and 5. A bolt 10 is inserted through the opening 9 and alined opening described and through a tubular member 11 that is embedded in the tie in such manner as to aline with the opening described. A nut 12 is turned upon the threaded end of the bolt and is countersunk within the top plate 4. If desired the bolt may be inserted through in an opposite direction so that the nut 12 is upon the outer face of the body portion of the member 8 and beneath the tie.

Laterally extending flanges 13 are formed on the upper end of the side plates. These flanges 13 are of the same width as the side plates and body portion of the member 8 and are flush on their upper faces with the top of the tie and also provided with apertures 14 formed therein.

As a means to receive and support the rails I provide at each end of the tie a rectangular rail supporting plate 15 that is formed on its longitudinal edges with upstanding

flanges 16 and bent downwardly and inwardly at its ends to provide hook portions 17 that are to coöperate with the end edges of the flanges 13 to prevent endwise movement of the plate 15 and otherwise hold the plate in the proper position. Openings 18 are formed in pairs in the plate 15 and aline with the openings 14 in the flanges 13. Threaded fastening members 19 are inserted 10 through the alined openings and have nuts 20 turned on their threaded terminals, to secure the plate 15 rigidly in position but so that it is readily removable. To attach the plate 15 it is only necessary to slide the hook ends 17 under the flanges 13 until they assume the position as shown in Fig. 3 in the drawings. The rails are positioned upon the plate 15 so that the sides of the bases thereof engage the inner faces of the flanges 16. It will be readily seen that I have provided a tie that is of extremely durable and rigid construction. The members 8 serve to brace the tie at the ends thereof and partially surrounding the same by the longitudinal plates 4 and 5 and increase the rigidity and strength of the tie.

To securely hold the ends of the rails at the joints upon the tie and in proper position, I provide angle bars 20^a of the ordinary construction that are arranged upon opposite sides of the rails at the points where the ends thereof meet. Inserted 30 through the angle bars 20^a and rails are screws or bolts 21 that are provided with circumferential grooves 22 adjacent to the heads thereof and which receive hooks 23 that are pivoted as at 24 upon the vertical portions of the angle bars 20^a and engage the screws in such manner that the screws are 40 prevented from coming out of position.

To prevent the hook moving out of engagement with the screw I provide a bowed leaf spring 25 that is secured at one end adjacent the pivoted end of each of the hooks 23 and has bowed portion so arranged as to frictionally engage the screw and disposed upon one side of the shank of the hook. The angle bars 20^a hold the rails securely in position. Screws or other suitable 50 elements 27 are inserted through the bases of the rails and member 15. The angle bars rest upon the screws or other suitable fastening elements 27 and hold them in position.

It will be readily seen that I have provided a simple, reliable and effective rail tie 55 and fastening means therefor that will serve in an extremely reliable manner to securely hold rails in such manner that slipping and spreading thereof is prevented as well as sinking.

In practice I have found that the form of my invention, illustrated in the drawings and referred to in the above description, as the preferred embodiment, is the most efficient and practical; yet realizing that the

conditions concurrent with the adoption of my device will necessarily vary, I desire to emphasize the fact that various minor changes in details of construction, proportion, and arrangement of parts may be resorted to, when required, without sacrificing any of the advantages of my invention, as set forth.

What is claimed is:—

1. A rail tie consisting of a concrete body 75 having longitudinal channels on its upper and lower faces, metal plates mounted within the channels and terminating flush with the ends of the tie at their ends, said body being provided upon opposite sides and adjacent to each end with vertical channels, a U-shaped binding member having its side portions disposed within the vertical channels at each end of the tie, bolts inserted through the body portions of the U-shaped 85 members, plates and body portion of the tie adjacent to the ends thereof, and rail clamping means carried upon the upper face of the body.

2. A rail tie consisting of a concrete body 90 having longitudinal channels on its upper and lower faces, metal plates mounted within the channels and terminating flush with the ends of the tie at their ends, said body being provided upon opposite sides and adjacent to each end with vertical channels, a U-shaped binding member having its side 95 portions disposed within the vertical channels at each end of the tie, bolts inserted through the body portions of the U-shaped 100 members, plates and body portion of the tie adjacent to the ends thereof, rail clamping means carried upon the upper face of the body, on the upper ends of the U-shaped members to support the rail clamping 105 means.

3. A rail tie consisting of a concrete body, rectangular plates of less width than the tie mounted within the bottom and top thereof and being flush at their ends and 110 outer faces with the tie, U-shaped members mounted upon the tie engaging the bottom and sides thereof, lateral flanges on the free ends of the U-shaped members, bolts inserted through the U-shaped members, tie 115 and plates, rail supporting means mounted on the tie at each end and engaging the lateral flanges, and means to secure the rail supporting means to the lateral flanges.

4. A rail tie consisting of a body portion, 120 U-shaped members mounted on the body portion at the ends thereof and engaging the bottom and sides thereof, lateral flanges on the free ends of the U-shaped portions and being flush with the upper face of the body 125 portion, rail holding plates mounted upon the body portion and engaging upon the flanges adjacent to their ends, means to secure the rail holding plates to the flanges, said rail holding plates being bent over and 130

underneath the ends of the flanges at their ends, longitudinal upstanding flanges on the sides of the rail holding plates to engage the sides of the bases of the rails and means to secure the rails to the rail supporting plates.

5. A rail tie consisting of a plastic body, plates mounted upon the top and bottom of the body and being embedded therein with their outer surfaces flushed with the outer surface of the body, U-shaped members mounted upon the body and engaging the bottom and sides thereof, lateral flanges on

the free ends of the U-shaped members, bolts inserted through the U-shaped members, tie and plates, and rail supporting means consisting of plates having hook ends mounted upon said body with the hook ends engaging the lateral flanges.

In testimony whereof I affix my signature in presence of two witnesses.

IDA CAREY.
